[57] CLAIM

The ornamental design for a gas fractionator for drying compressed air, as shown.

DESCRIPTION

FIG. 1 is a perspective view of a gas fractionator for drying compressed air embodying our new design.

FIG. 2 is a front elevational view thereof.

FIG. 3 is a right side elevational view thereof.

FIG. 4 is a left side elevational view thereof.

FIG. 5 is a rear elevational view thereof.

FIG. 6 is a top plan view thereof.

FIG. 7 is a bottom plan view thereof.
